Patented Nov. 2, 1926.

1,605,900

UNITED STATES PATENT OFFICE.

LESTER D. MOWREY, OF BURKBURNETT, TEXAS.

PUMP PISTON.

Application filed August 28, 1925. Serial No. 53,016.

This invention relates to improvements in oil well pumps and in such connection it relates more particularly to the novel arrangement and construction of the parts 5 thereof.

A particular object of the invention is to provide a pump of this nature having a traveling valve with cups and compression members in combination with a gas and sand 10 trap.

Another object of the invention is to provide compression members with related parts so arranged and constructed that they will maintain perfect packing contact to the 15 pump barrel.

A further object is that the compression members will provide inside expansion on the downward stroke of the pump, and give a circulating motion to the fluid and eliminating sediment on the compression 20 members and parts.

The new and improved combination pump and gas trap will be better understood by reference to the following detailed description taken in connection with the accompanying drawings forming part hereof and in which:

Figure 1 is a longitudinal sectional view of the pump in two sections, one section in 30 broken formation.

Figure 2 is a side view of the plunger in broken formation.

Figures 3, 4, 5 and 6 are cross-sectional views along the lines 3-3, 4-4, 5-5 and 35 6-6 respectively, of Figures 1 and 2.

Describing the drawing more in detail a plunger P is shown in two sections in Figure 2 with connection 1 to a sucker rod for reciprocating the plunger. The plunger has 40 a ball valve 3 and 4 and standing ball valve 5, and a liquid outlet 6 into the pump barrel 7.

On the upper end of the plunger P are disposed four compression members preferably of leather, the upper one 8 having a rounded portion 9 and having its upper edge disposed in an annular groove 10. The lower part of the compression member 8 is disposed under a shoulder 11 on the plunger. 45 The plunger as will be observed has spaced apertures 12-12 for the passage of the fluid against the compression members in the lifting operation of the liquid. Below the compression member 8 is a spacer ring 50 13 which closely fits the rounded portion 9 of the member. The spacer ring 13 has a

shoulder 14 to receive the bevelled edge of its compression member 14, the lower end of the member 14 enclosing the bottom edge of the ring 13. The next spacer ring 15 and compression member 16 are of the same construction as those just described. The bottom compression member 17 and its spacer ring 18 are likewise of the same construction, except that there are no perforations in the 60 plunger P adjacent these two last members.

Below the upper compression members and spacer rings is the ball valve 3 in its cage 19 with seat 20. The seat is the upper part of a head 21 which connects the plunger sections. Valve 4 is seated on the top of the lower plunger section.

On the lower plunger part are a plurality of compression members, 22, 23 and 24. It will be seen that this section of the plunger has a shoulder 23 to seat the first compression member 22 while the next two such members, 23-23 are carried on the spacer rings 26-26.

Particular attention is called to the last compression member 24 which is inverted and is spaced apart from the upper member 23. Attention is also directed to the fact that the lower compression member is the only one in the lower plunger section which has apertures 28. Below the members just described is the standing ball valve 5 which is seated in a head 29 connecting the sand trap. The sand trap is also in two sections 30-30 connected by a head 31.

The head 29 has spaced vertical chambers 32-32 for escaping gas passing upwardly between the pump barrel 7 and a tubular member 33 which extends above the plunger a short distance. The gas passes through the 45 annular space 34.

Secured to the head 32 is a tubular member 35 and surrounding the member 35 is a larger tubular member 36. A third tubular member 38 encloses member 36 and is secured to head 31, channeled at 39 for the passage of the liquid entering through the sand trap 30 through openings 40-40. The sand trap is closed at its lower end and has an inner pocket 41 also closed at the lower 50 end.

In the operation of the pump the oil entering apertures 40-40 on the upward stroke of the pump plunger is drawn inwardly and passes through channels 39-39 and between the tubular member 38 and the trap wall 30 10 in the direction of the arrows and passes

downwardly inside the member 38, thence upwardly into tubular member 36 and into the pump barrel. As the liquid is drawn upward at the point A sand will be drawn downward and fall into the trap member 41. Sand will also collect in member 30 as the oil enters.

On the upward stroke of the pump the oil entering the plunger and passing through the apertures 12—12 will force the members 11, 14, 16 and 17 against the barrel and produce a perfect packing contact to barrel. This operation also gives a circulating motion to the fluid and does not permit sediment to settle on compression members or plunger which would cause packing to cut and also cause plunger to stick in barrel. The perforations under the bottom cup provides inside expansion on the downward stroke of the pump.

What is claimed is:

1. An oil well pump comprising a pump barrel, a tubular plunger reciprocable in the pump barrel; a plurality of compression members on the upper part of the plunger, spacer rings between said compression members, spaced perforations in the plunger walls adjacent said compression members to cause the fluid on the upward stroke of the plunger to be forced through said perforations and against said compression members

to cause the latter to bear against the pump barrel; a plurality of compression members on the lower portion of the plunger, spacer rings between said lower disposed compression members, one of which has its rim directed downwardly and provided with perforations to permit the fluid to force it against the pump barrel on the downward stroke of the plunger; and ball valves between the upper and lower portions of said plunger.

2. An oil well pump, comprising a pump barrel, a tubular plunger reciprocable within the pump barrel, said plunger consisting of two sections joined by a connecting head, a ball valve on opposite ends of the head and a ball valve below the end of the plunger, openings in the top and bottom of said plunger for passage of liquid controlled by said valves; said plunger sections provided with a plurality of compression members, spaced perforations in the walls of the plunger sections, the compression members being separated by spacer rings, one of the compression members on the lower section of the plunger being inverted with its rim directed downwardly.

In testimony whereof I have signed my name to this specification.

LESTER D. MOWREY.
